CLAIM

The ornamental design for a golf shoe outsole, as shown and described.

DESCRIPTION

FIG. 1 is a perspective view of the golf shoe outsole showing our new design.

FIG. 2 is a bottom plan view thereof.

FIG. 3 is a top plan view thereof.

FIG. 4 is a left side elevational view thereof.

FIG. 5 is a right side elevational view thereof.

FIG. 6 is a rear elevational view thereof; and,

FIG. 7 is a front elevational view thereof.

The broken lines showing the shoe upper throughout the views represent the portions of the design that form no part of the claim. The broken outline forming the letters, "F & J" as well as the outermost broken lines forming the cleats define the boundaries of the design. The broken lines and the areas within them, form no part of the claim.
